UNITED STATES PATENT OFFICE.

THOMAS A. HAUGAARD, OF CHEYENNE, WYOMING.

ANNUNCIATOR SYSTEM.

1,095,112.

Specification of Letters Patent. Patented Apr. 28, 1914.

Application filed October 28, 1913. Serial No. 798,078.

To all whom it may concern:

Be it known that I, THOMAS A. HAUGAARD, a citizen of the United States, residing at Cheyenne, in the county of Laramie and 5 State of Wyoming, have invented new and useful Improvements in Annunciator Systems, of which the following is a specification.

This invention relates to improvements 10 in annunciator systems and has particular application to a clock controlled annunciator system for use in hotels, apartments and analogous places.

In carrying out the present invention, it 15 is my purpose to provide a system of the class described whereby a guest or guests in any room or number of rooms may be called automatically at any desired to predetermined time.

20 It is also my purpose to provide an annunciator system for use in hotels and the like places which will be entirely automatic in operation and which may be installed and maintained at a minimum expense.

25 With the above and other objects in view, the invention consists in the construction, combination and arrangement of parts hereinafter set forth, in and falling within the scope of the claims.

30 In the accompanying drawings; Figure 1 is a view in front elevation of a chronometer and associated parts of an annunciator system constructed in accordance with my present invention. Fig. 2 is a view in end 35 elevation thereof. Fig. 3 is a fragmentary vertical sectional view through the same. Fig. 4 is a horizontal sectional view therethrough, parts being shown in bottom plan. Fig. 5 is an enlarged fragmentary face view 40 of the dial of the chronometer. Fig. 6 is a fragmentary vertical sectional view therethrough, parts being shown in elevation. Fig. 7 is a fragmentary horizontal sectional view through the switch board. Fig. 8 is 45 a longitudinal sectional view through one of the jacks on the switch board. Fig. 9 is a top plan view thereof. Fig. 10 is an end elevation of the same. Fig. 11 is a view in side elevation of one of the plugs, parts being shown in section. Fig. 12 is a fragmentary diagrammatic view showing the 50 circuit connections between the chronometer and a guest room. Fig. 13 is a diagrammatic view showing the connections between the chronometer and switch board.

Referring now to the accompanying draw-

ings in detail, A designates a switch board comprising a base or table 1 of any suitable construction and a vertical slab or panel 2 uprising from the base 1 at the rear edge 60 of the latter and constructed of any suitable material. Suitably secured to the front face of the slab 2 are vertical strips 3 having the adjacent side edges insulated one from another by strips of insulation 4 and capable of conducting an electric current. 65 Embedded in each conducting strip 3 are a plurality of metallic jacks 5 arranged in a vertical row and suitably spaced apart and each electrically connected with the conducting strip. In the present instance, I have shown the switch board as composed of forty-eight vertical conducting strips each equipped with fifteen jacks. Each jack is preferably, although not necessarily, 70 composed of a cylindrical metallic sleeve 5 stamped at diametrically opposite points to provide inwardly projecting friction tongues 6 and having the outer edge thereof flanged as at 7 and embedded within the respective 75 strip on the switch board. Seated within recesses formed in the upper surface of the table 1 adjacent to the lower end of the slab or panel 2 are plugs 8 spaced apart longitudinally of the table, while secured to 80 the under surface of the table top adjacent to each plug 8 is a metallic strip 9 equipped at one end with a binding post 10 and having the opposite end downturned as at 11 and formed with an eye designed to receive 85 one terminal of an electric current carrying cord 12, the free terminal of the cord 12 being fastened to the plug 8 as at 13. Suspended from each cord 12 by means of a sheave 14 is a weight 15 acting to hold the 90 respective plug 8 normally seated. In the embodiment of my invention selected for 95 illustrative purposes, the plugs 8 are fifteen in number, corresponding with the number of jacks in each vertical strip of the switch board and such plugs are interchangeable with the jacks so that all of such plugs may be inserted within the jacks in one strip, if such is desired, or may be scattered over 100 the panel.

105 Appropriately fastened to the upper edge of the panel 2 is a block 16 having the upper edge thereof concaved and seated within the concavity in the block is a chronometer 17 in the form of a clock. Inclosing the dial of 110 the chronometer concentrically thereof is a metallic conducting ring 18, while surround-

ing the ring 18 is an annulus 19 composed of insulating material, the ring 18 and the annulus 19 being embedded in the face of the chronometer. Projecting outwardly from the outer edge of the conducting ring 18 and spaced apart equal distances about such ring are pivot pins 20 upon each of which is fulcrumed between its ends a switch lever 21 having the outer end thereof overlying the insulated ring 19 and the inner end rounded off as at 22 and disposed in the path of movement of the outer extremity of the spring finger 23 carried by one of the indicating hands of the chronometer, the hour hand in the present instance. In this form of my invention, one switch lever 20 is disposed adjacent to each hour mark while three switch levers are interposed between adjacent hour marks and spaced apart equal distances. For instance, one lever is disposed adjacent to the hour mark 12 on the dial of the clock while three levers are interposed between such hour mark and the hour 1, these last levers representing 15, 30 and 45 minutes after the hour 12. Embedded in the insulated ring 19 are contact pins 24 corresponding in number with the switch levers and each disposed immediately adjacent to the outer end of one of such levers. Arranged adjacent to the inner end of each switch lever is a stop pin 25 while fastened to each lever upon the inner side of the fulcrum point thereof is one extremity of a coiled contractile spring 26 having the other end thereof secured to the dial of the chronometer as at 27, such springs acting to maintain the levers normally out of engagement with the contact pins 24. These pins 24 and contact levers together with the conducting ring 18 constitute a circular series of switches arranged concentrically of the dial of the clock and corresponding in number to the number of conducting strips 3 on the switch board and, as illustrated in Fig. 13, each contact pin 24 is wired up to one of the conducting strips 3 by means of a conductor 28. By means of this construction, it will be seen that as the hour hand of the clock moves over the face of the dial the switch levers will be actuated successively to engage the respective contact pins 24 thereby forming an electrical connection between the conducting ring 18 and the vertical strips on the switch board, the springs 26 restoring the switch levers to normal position succeeding the release of such levers by the finger 23 on the hour hand, it being understood that the finger 23 maintains each lever in engagement with the respective contact pin for an appreciable length of time.

Each binding post 10 electrically connected with a plug 8 is connected to one terminal of a conductor 29 leading to one side of an annunciator 30 located in a guest's room or other similar place and from the

opposite side of the annunciator leads a conductor 31. The conductors 31 leading from the various annunciators are connected to one side of a supply circuit 32 including a suitable source of electrical energy such, for instance, as a battery 33, while the conducting ring 18 is tapped onto the opposite side of such supply circuit by way of a conductor 34.

To illustrate the operation of the invention, we will assume that a guest desires to be called at 6.30 o'clock. Such being the case, the operator in charge of the switch board inserts the plug 8 connected with the annunciator in the particular guest's room into one of the jacks in the circuit conducting strip 3 connected with the contact pin 24 in the path of movement of the central lever 21 of the three between the hours 6 and 7. When the minute hand of the clock has moved to the proper position, the hour hand will be at a point approximately centrally of the numerals 6 and 7 on the clock dial so that the finger 23 will contact with the inner end of the adjacent lever 21 and so swing the latter about its pivot pin 20 whereby the outer end of the lever will engage the adjacent contact pin 24, thereby completing the contact circuit to the annunciator 30 in the respective guest's room so that such respective annunciator will be energized, current flowing from one side of the battery 33 through the common wire 34, the ring 18, pin 26, the particular lever 21, the contact pin 24 in engagement with such contact pin, the particular strip 3 on the switch board, plugged jack within such strip, the cord 12, connector 9, binding post 10, wire 29, annunciator, conductor 31 and back to the other side of the battery 33 by way of the respective conductor 32.

Should it be desired to call a number of guests at one time all of the plugs connected with the annunciators in the rooms of such guests are plugged into the jacks of the proper conducting strip on the switch board so that when the hour hand of the clock has reached the desired point all of such annunciators will be sounded upon the operation of the particular switch lever.

From the foregoing description taken in connection with the accompanying drawings, the construction, mode of operation and manner of employing my invention will be readily apparent. It will be seen that I have provided an annunciator system for hotels, rooming houses and the like whereby any one or all of the guests in the hospitality may be called at any desired time.

While I have herein shown and described one preferred form of my invention by way of illustration, I wish it to be understood that I do not limit or confine myself to the precise details of construction herein described and delineated, as modification and

variation may be made within the scope of the claims without departing from the spirit of the invention.

I claim:

- 5 1. In an annunciator system, a chronometer, a circular series of switches arranged concentrically of the dial of said chronometer and comprising a conducting ring, switch levers fulcrumed upon said ring, an
 10 insulated ring disposed concentrically of said conducting ring, contact pins carried by said insulated ring and each disposed adjacent to one of said levers, means whereby any annunciator may be connected in circuit with any one switch, and a finger carried by the hour hand of said chronometer for actuating said switch levers successively.
- 15 2. In an annunciator system, a chronometer, a circular series of switches arranged concentrically of the dial of said chronometer and comprising a conducting ring, switch levers fulcrumed upon said ring, an insulated ring disposed concentrically of said conducting ring, contact pins carried by said insulated ring and each disposed adjacent to one of said levers, means whereby any annunciator may be connected in circuit with any one switch, a finger carried by the hour hand of said chronometer for actuating said switch levers successively,
- 20 3. In an annunciator system, a chronometer, a circular series of switches arranged concentrically of the dial of said chronometer and comprising a conducting ring, switch levers fulcrumed upon said ring, an insulated ring disposed concentrically of said conducting ring, contact pins carried by said insulated ring and each disposed adjacent to one of said levers, means whereby any annunciator may be connected in circuit with any one switch, a finger carried by the hour hand of said chronometer for actuating said switch levers successively,
- 25 4. In an annunciator system, a chronometer, a circular series of switches arranged concentrically of the dial of said chronometer and comprising a conducting ring, switch levers fulcrumed upon said ring, an insulated ring disposed concentrically of said conducting ring and surrounding the same, contact pins carried by said insulated ring and each disposed in the path of movement of the outer end of one of said levers, means whereby any annunciator may be connected in circuit with any one switch, a finger carried by the hour hand of said chronometer for actuating said switch levers successively whereby the outer ends of said levers will engage the respective contact pins.
- 30 5. In an annunciator system, a chronometer, a circular series of switches arranged concentrically of the dial of said chronometer and comprising a conducting ring, switch levers fulcrumed upon said ring, an insulated ring disposed concentrically of said conducting ring, contact pins carried by said insulated ring and each disposed adjacent to one of said levers, means whereby any annunciator may be connected in circuit with any one switch, a finger carried by the hour hand of said chronometer for actuating said switch levers successively,
- 35 6. In an annunciator system, a chronometer, a circular series of switches arranged concentrically of the dial of said chronometer and comprising a conducting ring, switch levers fulcrumed upon said ring, an insulated ring disposed concentrically of said conducting ring, contact pins carried by said insulated ring and each disposed adjacent to one of said levers, means whereby any annunciator may be connected in circuit with any one switch, a finger carried by the hour hand of said chronometer for actuating said switch levers successively,

7. In an annunciator system, a chronometer, a circular series of switches arranged concentrically of the dial of said chronometer and comprising a conducting ring, switch levers fulcrumed upon said ring, an insulated ring disposed concentrically of said conducting ring, contact pins carried by said insulated ring and each disposed adjacent to one of said levers, means whereby any annunciator may be connected in circuit with any one switch, a finger carried by the hour hand of said chronometer for actuating said switch levers successively,

8. In an annunciator system, a chronometer, a circular series of switches arranged concentrically of the dial of said chronometer and comprising a conducting ring, switch levers fulcrumed upon said ring, an insulated ring disposed concentrically of said conducting ring and surrounding the same, contact pins carried by said insulated ring and each disposed in the path of movement of the outer end of one of said levers, means whereby any annunciator may be connected in circuit with any one switch, a finger carried by the hour hand of said chronometer for actuating said switch levers successively whereby the outer ends of said levers will engage the respective contact pins.

In testimony whereof I affix my signature in presence of two witnesses.

THOMAS A. HAUGAARD.
